UNITED STATES PATENT OFFICE.

EDWIN B. STIMPSON, OF BROOKLYN, NEW YORK.

SHOE-SHANK.

1,208,397.

Specification of Letters Patent. Patented Dec. 12, 1916.

Application filed June 8, 1914. Serial No. 843,762.

To all whom it may concern:

Be it known that I, EDWIN BALL STIMPSON, a citizen of the United States, residing at Brooklyn, in the county of Kings and State of New York, have invented certain new and useful Improvements in Shoe-Shanks, of which the following is a specification.

This invention relates to shoes, and particularly to a new and useful construction of shoe shank for stiffening the arched inner and outer sole portions of a shoe, and in the relation of such shank to the inner and outer sole and heel. These shanks are usually secured at their forward ends to one or the other of the two soles between which they lie. Usually holes are formed in the end of the shank and rivets or the like fastening members are driven through the two soles and the shank. The difficulty is in locating the holes with the rivet or nail.

It is one of the objects of my invention to overcome this practical difficulty by making the forward end of the shank of softer metal than the rest of the shank, so that a nail or fastening device may be driven through at any point in the soft metal portion, without the necessity of previously providing an opening therein. This I may accomplish for instance by annealing the forward end of the usual steel shank, so as to make the forward end soft.

Another object of the invention is to provide the rear end of the shank with means for attaching it to the heel and also for predeterminedly fixing the relation of the shank to the heel.

Another object of the invention is to provide a cap for the forward end of the shoe within which the end of the shank is longitudinally slid able, the said cap being provided with a forward extension through which the fastening means is to be driven.

Many other advantages of the invention will appear from a consideration of the following description thereof.

In the accompanying drawings, which are to be taken as a part of this specification, and in which I have shown an embodiment of the invention as at present preferred, Figure 1 is an elevation partly broken away

and partly in section, showing the application of my invention to an ordinary shoe; Fig. 2 is a detail side view of the shank with its cap; Fig. 3 is a plan of the same; and Fig. 4 is a section on the line 4—4 of Fig. 2.

Referring to the numerals on the drawings, 6 and 7 indicate inner and outer arched sole portions of a shoe, and between them appears a shank 8, arched to correspond, and having generally flat faces. The rear end of the shank is bifurcated, as shown in Fig. 3, and between the bifurcations there is a downwardly extending portion 9. The bifurcated portions of the shank are secured to the upper face of a heel 11, while the downwardly extending portion 9 contacts with the forward face 12 of the heel, and predetermines, by its arrangement with such face 12, the relation of the shank to the heel. Furthermore, by this arrangement the fastening of the shank to the heel is made very much stronger, as will be obvious, and it insures that the forward end of the shank, which is preferably to be fastened between the inner and outer soles, and to one or both of them, will have a predetermined position.

14 indicates a cap for the forward end of the shank, which may be made of a generally flat piece of metal having its sides 16 bent over so as to inclose the forward end of the shank. The bent portions 15 are provided with depressions 16 which serve to limit the forward sliding movement of the end of the shank within the cap, and preferably there is provided a forward extension 17 on the cap. It being understood that the cap is made of softer metal than the shank, it will be evident that when the shank has been fastened to the heel, the cap 14 may be put over the forward end of the shank and inserted therewith between the inner and outer soles, until the capped end of the shank reaches the position shown in Fig. 1; while the heel takes the position which it occupies in that figure. A rivet or fastener is now driven through the soles and through the extension 17 of the cap, in order to hold the latter in place. If the shank is flexed in walking, the forward end of the shank may slide back and forth within the cap, to

allow for such flexing. At the same time, the cap maintains its relation relatively to the soles, which is desirable.

I claim:

- 5 A shoe-shank and cap therefor, said cap having a bottom wall and bent-over side portions between which and the bottom the end of the shank is slideable and by which the shank is restrained against lateral move-

ment, said bottom wall having an integral 10 forward extension.

In testimony whereof I affix my signature in presence of two witnesses.

EDWIN B. STIMPSON.
